UNITED STATES PATENT OFFICE.

JAMES J. CLIFFORD, OF GREEN ISLAND, NEW YORK, ASSIGNOR TO JAMES J. CLIFFORD & CO., OF GREEN ISLAND, NEW YORK, A FIRM.

DEMIJOHN-CRATE.

SPECIFICATION forming part of Letters Patent No. 723,649, dated March 24, 1903.

Application filed March 28, 1902. Serial No 100,408. (No model.)

To all whom it may concern.

Be it known that I, JAMES J. CLIFFORD, a citizen of the United States, residing at Green Island, county of Albany, and State of New York, have invented certain new and useful 5 Improvements in Demijohn-Crates, of which the following is a specification.

The invention relates to such improvements; and it consists of the novel construction and combination of parts hereinafter described and subsequently claimed.

Reference may be had to the accompanying drawings, and the reference characters marked thereon, which form a part of this 15 specification.

Similar characters refer to similar parts in the several figures.

Figure 1 of the drawings is a top plan view of my improved demijohn-crate, showing a 20 demijohn secured therein. Fig. 2 is a vertical section taken diagonally of the crate upon the broken line 2-2 in Fig. 1. Fig. 3 is a view in perspective of my improved buffer detached.

25 The object of my invention is to provide a simple and efficient buffer for demijohn-crates and the like and to secure the demijohn within the crate.

Referring to the drawings, 1 represents the 30 frame of the crate, preferably of rectangular form, with sides of equal dimensions and provided with triangular corner-posts 2, set into the angles of the frame in the usual manner. My improved buffers are mounted upon these 35 corner-posts in position to engage the sides of a demijohn 3, contained within the crate. These buffers comprise, preferably, each a strip 4, of hickory or other tough and resilient wood, bent to bow form by having its ends 5 bent back parallel with the body of the strip, forming upper and lower bends or loops 6. The ends of the buffer-strip are provided with apertures 7, adapted to receive a key 8, passed therethrough and through a similar 40 aperture in the corner-post 2, whereby the buffer is secured to said post. The parts are so arranged that the space between two diagonally opposed buffers is somewhat less than the diameter of the demijohn, so that 45 when the demijohn is inserted in the crate between the buffers the latter are compressed

and forced apart by the demijohn, causing them to bear with more or less friction upon the sides of the demijohn, holding the latter securely in place, as well as protecting the 55 same from sudden shocks. The corner-posts are preferably cut away at their upper and lower ends opposite the bends 6 in the buffer-strips to form rocker-seats 9 for the attaching ends of the strips, whereby a considerable yielding movement of the buffer is permitted.

While I prefer to use hickory or other tough wood for the buffer-strips, they may be made 60 of any strong resilient material.

The demijohn is further held in place in the crate by means of a strap formed of a single piece of wire bent double and having the bend 10 therein, forming a hinge connection with the upper bend or loop 6 of one of the 70 buffer-strips and provided with introverted hook-terminals 11, adapted to detachably interlock with the upper bend or loop 6 in the diagonally opposite buffer-strip. In applying the strap to the crated demijohn the branches 75 of the double wire are crossed at 12 between the neck of the demijohn and one of the connecting-buffers and at 13 between the neck of the demijohn and the other connecting-buffer, being thus caused to closely embrace be- 80 tween their middle portions the neck of the demijohn and after the hooks 11 are fastened effectually preventing the escape of the demijohn from the crate, even though inverted. When the two diagonally opposite buffers are 85 connected by means of the wire strap passing above the body of the demijohn, any movement of the demijohn outwardly would, by forcing outwardly the engaged middle portion of the wire strap, cause the strap-con- 90 nected buffers to be drawn toward each other to more tightly engage the interposed demijohn to prevent further movement of the same.

By providing the several corner-posts with an upwardly and outwardly retreating rocker-seat 9 and a loose connection between the retroverted end of the buffer-strip and the corner-post, as by the key 8, the retroverted end of the strip is permitted to rock upon the rocker-seat to allow the upper end of the buffer to yield more readily for the insertion of the bottle, while after the bottle is seated in 95 100

the crate the engagement of the body of the bottle with the middle part of the buffer tends to prevent such rocking movement and to hold the bottle securely in position.

5 What I claim as new, and desire to secure by Letters Patent, is—

1. In a demijohn-crate, the combination with the crate-frame having a corner-post provided with an upwardly and outwardly retreating rocker-seat; of a buffer comprising a resilient strip having an end retroverted to form a U-shaped bend and adapted to bear upon said rocker-seat; and a loose connection between said retroverted end of the buffer-strip and said corner-post adapted to permit rocking movement of one of said parts on the other, substantially as described.

2. In a demijohn-crate, the combination with the crate-frame, of a locking-strap comprising a piece of wire bent double forming at the bend a hinge connection with the frame, and having hook-shaped terminals adapted

to form a detachable connection with said frame on the opposite side of the crate, the branches of said doubled wire being adapted 25 to closely embrace the neck and overhang the body of a demijohn contained within the crate, substantially as described.

3. In a demijohn-crate, the combination with the crate-frame open at one end; of buffers oppositely disposed within said frame and capable of movement toward and from each other; and a strap connection between said buffers extending across the open end of the frame, and adapted to overhang the 35 body of a demijohn confined between the strap-connected buffers, substantially as described.

In testimony whereof I have hereunto set my hand this 20th day of March, 1902.

JAMES J. CLIFFORD.
